CLAIM

The ornamental design for a phone or tablet stand, as shown and described.

DESCRIPTION

FIG. 1 is a perspective view of a phone or tablet stand showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the phone or tablet stand thereof but shown in use with broken line environment;

FIG. 10 is a perspective view of the phone or tablet stand thereof but showing an alternate position; and,

FIG. 11 is a perspective view of the phone or tablet stand thereof but showing another alternate position.

The broken lines in the drawings depict portions of the phone or tablet stand that form no part of the claimed design.
